UNITED STATES PATENT OFFICE.

ANDERSON PITT ROBERTS AND WILLIAM MARVIN ROBERTS, OF COLUMBIA, TENNESSEE.

PNEUMATIC STACKER.

SPECIFICATION forming part of Letters Patent No. 755,940, dated March 29, 1904.

Application filed January 13, 1903. Serial No. 138,863. (No model.)

To all whom it may concern:

Be it known that we, ANDERSON PITT ROBERTS and WILLIAM MARVIN ROBERTS, citizens of the United States, residing at Columbia, in the county of Maury and State of Tennessee, have invented certain new and useful Improvements in Pneumatic Stackers, of which the following is a specification.

Our invention relates to pneumatic stackers such as are employed in connection with husking-machines; and it has for one of its objects to provide a construction in which the usual complicated mechanism or gearing between the drive-shaft and the tube or its support is dispensed with, a further object of the invention being to provide a mechanism wherein there will be a more direct transmission of energy from the drive-shaft to the stacker discharge-tube and in which the operation of the mechanism will not be likely to be interfered with by flying husks or other matter.

A further object of the invention is to simplify the construction of the driving mechanism by a reduction in the number of elements composing such mechanism.

A further object of the invention is to provide a simple and efficient means for giving to the stacker discharge-tube an oscillatory movement by a "direct connection" leading from a continuously-rotating drive-shaft.

A still further object of the invention is to provide a shifting or reversing mechanism of a simple and efficient construction and one wherein the shifting or reversing of the discharge-tube is also accomplished by a direct connection between the said mechanism and the discharge-tube.

Other objects and advantages of the invention will be understood from the following description, taken in connection with the accompanying drawings.

Heretofore in the construction of pneumatic stackers there has in most instances, if not all, been employed numerous shafts and connections united and operated through the instrumentality of beveled gears and pinions or their equivalents; but it will be noted in the present instance that the driving mechanism is composed of a single drive-shaft and lead-

ing therefrom a direct connection, there being shown a cable-drive to oscillate the tube, all gears and pinions being entirely omitted as far as the oscillation of the discharge-tube is concerned. It has also been found in most instances, if not all, that the tripping or reversing of the tube has been accomplished through the medium of one lever coacting with another or through the medium of bell-crank levers, while in the present instance the shifting or reversing mechanism is carried by the drive-shaft, a direct connection or a single lever leading therefrom to and actuated by the discharge-tube. Where numerous shafts and gears are employed, the transmission of energy is more or less retarded and reduced in power, for the reason that the energy in taking irregular or what might be termed "right-angular" directions loses energy, while in the present instance by our direct connections—that is, one direct connection between the driving mechanism and the tube for oscillation purposes and another direct connection for reversing the direction of movement of the tube to permit of its oscillation—energy as regards the oscillation and reversing of the discharge-tube is neither retarded nor reduced, the construction greatly simplified, hence a more economical and compact arrangement, with less liability of derangement of the driving mechanism.

In the drawings forming a portion of this specification, and in which like numerals of reference indicate similar parts in the several views, Figure 1 is a perspective view illustrating a stacker discharge-tube equipped with the present invention. Fig. 2 is a transverse section through the stacker-tube above the turn-table or tube-support and showing the winding-drums and the shifting-clutch mechanism in plan. Fig. 3 is a section taken vertically through the lower portion of the stacker-tube and including the drive-shaft and the shiftable member of the clutch, the shifting member of the clutch being in elevation. Fig. 4 is a vertical section taken longitudinally through the drive-shaft, and Fig. 5 is a vertical sectional view illustrating a modified form of mounting or supporting

means for the discharge - tube. Fig. 6 is a vertical sectional view of the master-wheel or support, illustrating a modified connection of the cable-drive thereto.

- 5 Referring now to the drawings, there is shown a portion of the frame 10 of a husking-machine, on which is mounted the fan-casing 11, having a fan 12 therein, and from which casing leads the upwardly-directed spout 13, 10 through which the husks pass from the casing into the discharge-tube. At the outer end of the frame 10 is the platform 14, having an opening 15, in which is secured the plate 16, having a flange 17, and in which opening engages the upper end of the spout 13.

The stacker discharge-tube 18 rises from a turn-table or revolving support 19 in the form of a circular plate having a depending flange 20, which fits over the flange 17 and 20 is spaced slightly therefrom, so that bearing-balls 21 may be held between the two flanges and rest upon the plate 16 while supporting the turn-table or support 19. These balls thus prevent lateral displacement and give a 25 lateral bearing for the turn-table or support in addition to supporting the latter.

The turn-table or support 19 has a central opening which is surrounded by the flange 22, which in turn has a flange 23 at its upper 30 edge, so that the flange 22 is in reality a drum to receive the actuating-cable 24, hereinafter described, the flange or drum receiving the lower end of the discharge-tube, which is secured firmly thereon, so that as the turn-table or support is oscillated similar movement will be given to the discharge-tube. To hold the turn-table or support down upon its 35 bearings, idlers 25 are provided and are mounted upon stub-shafts 26, carried by 40 brackets 27, which are mounted upon the platform 14 in position to hold the idlers against the upper face of the turn-table. By thus holding the turn-table against upward movement tilting of the discharge-tube is 45 prevented.

Upon the platform 14 are provided bearings 28, in which is journaled a drive-shaft 29 for actuating the discharge-tube, and this drive-shaft has a pulley 30 at one end which 50 receives a belt 31, leading to a pulley 32 on the shaft 33, from which the fan 12 is driven, so that the fan-shaft and the discharge-tube drive-shaft may be operated one from the other, it being understood, however, that the 55 drive-shaft may be rotated from any suitable source.

Upon the drive-shaft 29 are loosely mounted winding-drums 35 and 36, which are free to rotate upon the shaft, but are held against 60 longitudinal movement thereof, and on the mutually-adjacent faces of these winding-drums are formed clutch members 37 and 38. Upon the drive-shaft between the two clutch or winding drums is mounted a sleeve 39, 65 which is splined to the shaft so that it may

be shifted longitudinally thereof and rotated with the shaft, the ends of the sleeve 39 having clutch-faces 40 and 41 for alternate engagement with the clutches of the winding-drums, respectively, as the sleeve is shifted 70 longitudinally. Thus it will be seen that if the drive-shaft is continuously rotated and the clutch-sleeve is shifted longitudinally first in one direction and then the other first one winding-drum and then the other will be engaged with or connected to the shaft for rotation thereby. The winding-drums 35 and 36 are flanged, as shown, and are provided with a hood or casing 42, (shown in dotted lines in Fig. 3,) it being obvious that the hood 80 may extend entirely over the shaft and other mechanism, and through one flange of each drum is formed a perforation in which is engaged one end of a cable 24, the bight portion of which is wound upon the central flange or 85 drum of the turn-table or support and secured thereto through the perforations 44 and 44^a, as shown, there being a sufficient number of windings of the cable on the last-named drum to insure sufficient friction to cause the 90 drum to rotate when the cable is drawn therefrom in either direction. To shift the clutch-sleeve, a lever 45 is provided and is mounted at its outer end to the bracket 46, which is attached to the platform or table 14, said lever 95 having a lug 47 on its upper face, which lies between the spaced circumscribing flanges 48 and 49 of the sleeve 39, so that when the lever is moved in either direction the sleeve 39 will be correspondingly shifted. The lever 100 100 extends beneath a keeper or guide 50, secured upon the platform 14, and into path of movement of two pins or strikers 51 and 52, which depend from the turn-table or support 19 at diametrically opposite points of the latter, it being seen that the strikers may be interchangeable with the several perforations 105 formed in the turn-table or support for permitting different degrees of reverse movement of the latter. Pivoted to the keeper 50 is a 110 rod 53, the opposite end of which is passed loosely through a lug 54 on the shifting-lever between the keeper or guide and the point of engagement of the strikers, and upon this pivoted rod is disposed a helical spring 55, 115 which presses against the lug and the enlarged head of the rod and acts to hold the lever yieldably at whichever limit of lateral movement it be placed. It will thus be seen that if the drive-shaft be rotated continuously that 120 that winding-drum which is clutched thereto will be rotated to wind thereon the connected end of the cable to give to the stacker-tube and its support a corresponding rotary movement. This direction of movement or rotation of 125 the stacker-tube will be continued until a striker is brought into engagement with the shifting-lever and has moved the latter beyond the point of pivotal mounting of the rod which has been placed under tension by the 130

initial movement of the lever and will act to throw the lever to the opposite limit of its movement and engage the clutch-sleeve with the opposite winding-drum on the drive-shaft, 5 at the same time disengaging the sleeve from the first winding-drum. The second winding-drum will then be caused to rotate with the shaft, while the first winding-drum is free to rotate on the shaft, and in consequence the opposite end of the cable will be wound up and the cable will be drawn from the drum of the discharge-tube to rotate the same in opposite direction, it being noted that the cable is wound in opposite planes alternately. It will also be 10 seen that the shifting of the clutch-sleeve is automatic. Hence by continuously rotating the drive-shaft the discharge-tube will be oscillated.

In Fig. 5 there is shown a modification of 20 the mounting of the lower end of the stacker-tube in which there is employed a base-plate 60, which is bolted or otherwise secured to the platform 14 and through which is a central opening 61, which receives the lower end 25 of the stacker-tube, the lower end of the tube having a flange 62, which engages against the under side of the platform and prevents upward movement and tilting of the stacker-tube. Upon the stacker-tube above the plate 30 60 is a plate or flange 63, which bears upon the plate 60 and above which is a winding-drum 64, which receives the operating-cable 24 for oscillating the stacker-tube. It will be noted that the winding-drum 64 is formed integral with the flange 63, it being understood, 35 however, that this flange and its winding-drum might be formed in separate pieces.

It will be noted in our modified form of invention, particularly as regards the mounting 40 of the discharge-tube, that the latter extends beneath the under surface of the platform 14 and upward movement thereof is prevented by the collar or flange 62, while in the first-described form the discharge-tube is mounted 45 directly upon the drum of the support, turn-table, or, as it is sometimes called, the "master-wheel." It will also be noted that the plate 60 has an upwardly-directed flange 65 and that the flange 63 has a depending flange 50 66 fitting around the flange 65, but slightly spaced therefrom, and bearing-balls 67 disposed between the said flanges to prevent lateral displacement and permit of easy oscillation of the stacker-tube. It will further be 55 understood that the flange 63 is, like the support or turn-table 19, provided with interchangeable pins or strikers 68 for engagement with the reversing means already described.

In our modified form it may be desired to 60 eliminate the bearing-balls, and, if so, it is obvious that the flanges 65 and 66 of the plate 60 and the flange 63, respectively, would be more closely related—that is, that the flange 66 would loosely engage around or within the

flange 65—that undue wabbling of the stacker-tube in the absence of the bearing-balls might be prevented.

As illustrated in Fig. 6 of the drawings, the cable 24 for turning the master-wheel or tube-support may be formed in sections, one end 70 of each section being connected to the pulleys 35 and 36 (see Fig. 1) with each opposite end thereof knotted or otherwise secured in the perforations 44 and 44^a, as clearly shown in Fig. 6.

It is to be understood that our invention is subject to changes in forms and proportions, and modifications may be subsequently resorted to in the embodiment of our invention to which we consider ourselves entitled in so far as we do not depart from the spirit and scope of our invention.

We claim—

1. A stacker provided with an oscillatory tube, a driving mechanism consisting of a single drive-shaft rotating continuously in one direction, a reversing mechanism carried by the drive-shaft, and a direct connection between the driving mechanism and the tube for oscillating the latter.

2. A stacker provided with an oscillatory tube, a driving mechanism consisting of a single drive-shaft rotating continuously in one direction, and a direct connection between the drive-shaft and the tube for oscillating the latter.

3. A stacker provided with an oscillatory tube, a driving mechanism consisting of a single drive-shaft rotating continuously in one direction, a reversing mechanism mounted upon the drive-shaft, a direct connection between the reversing mechanism and the tube for reversing the movement of the latter, and another direct connection between the driving mechanism and the tube for oscillating the latter.

4. A stacker provided with an oscillatory tube, a driving mechanism consisting of a single drive-shaft rotating continuously in one direction and carrying a reversing mechanism, and a direct connection between the reversing mechanism and the tube for reversing the movement of the latter.

5. A stacker provided with an oscillatory tube, a drive-shaft rotating continuously in one direction, a direct connection between the tube for oscillating the latter, and means for reversing the movement of the tube.

6. A stacker provided with an oscillatory tube, a driving mechanism consisting of a single drive-shaft rotating continuously in one direction, and a direct flexible connection between the shaft and the tube for oscillating the latter.

7. A stacker provided with an oscillatory tube, a driving mechanism consisting of a single drive-shaft rotating continuously in one direction, a flexible connection between the

drive-shaft and the tube for oscillating the latter, and means for automatically reversing the movement of the tube.

8. A stacker provided with an oscillatory tube, a driving mechanism consisting of a single drive-shaft rotating continuously in one direction, a direct flexible connection between the drive-shaft and the tube for oscillating the latter, and another direct connection between the driving mechanism and the tube for reversing the movement of the tube.

9. A stacker provided with an oscillatory tube, a drive-shaft rotating continuously in one direction and carrying a reversing mechanism and driving members, and a direct connection between the driving members and the tube for oscillating the latter.

10. A stacker provided with an oscillatory tube, a drive-shaft rotating continuously in one direction and carrying a reversing mechanism and driving members, a direct connection between the driving members and the tube for oscillating the latter, and means for automatically actuating the reversing mechanism.

11. A stacker provided with an oscillatory tube, a drive-shaft rotating continuously in one direction and carrying a reversing mechanism and driving members, and a direct flexible connection between the driving members and the tube for oscillating the latter.

12. A stacker provided with an oscillatory tube, a drive-shaft carrying driving members, an automatically-arranged reversing mechanism disposed between the said members and communicating with said tube by a direct connection, and a direct flexible connection between the driving members and the tube for oscillating the latter.

13. A stacker provided with an oscillatory tube, a drive-shaft carrying reversing mechanism and driving members, said reversing mechanism being in direct communication with the tube and placed under tension during the oscillation of the latter, and a direct connection between the driving members and the tube for oscillating the latter.

14. A stacker provided with an oscillatory tube, a drive-shaft rotating continuously in one direction and carrying a reversing mechanism and driving members, a direct flexible connection between the driving members and the tube for oscillating the latter, and means carried by the tube for actuating the reversing mechanism.

15. A stacker provided with an oscillatory tube, a drive-shaft carrying a reversing mechanism and driving members, a direct connection between the driving members and the tube for oscillating the latter, and another direct connection between the driving mechanism and the tube for reversing the movement thereof.

16. A stacker provided with an oscillatory tube, a driving mechanism consisting of a single drive-shaft rotating continuously in one

direction and carrying driving members, a reversing mechanism mounted upon the shaft between said driving members and adapted to alternately engage said members, and a direct connection between the reversing mechanism and the tube for reversing the movement of the latter.

17. A stacker provided with an oscillatory tube, a driving mechanism consisting of a single drive-shaft rotating continuously in one direction and carrying driving members, a direct connection between the driving members and the tube for oscillating the latter, a reversing mechanism mounted upon said shaft between the said driving members and adapted to alternately engage said members, and a direct connection between the reversing mechanism and the tube for reversing the movement of the latter.

18. A stacker provided with an oscillatory tube, a driving mechanism consisting of a single drive-shaft rotating continuously in one direction and carrying driving members, a reversing mechanism mounted upon said shaft and automatically actuated, and a direct flexible connection between the driving members and the tube for oscillating the latter.

19. A stacker provided with an oscillatory tube, a driving mechanism consisting of a shaft and driving members carried thereon, a reversing mechanism mounted upon said shaft between said driving members and adapted to alternately engage said members, and a direct connection between the reversing mechanism and the tube for reversing the movement of the latter.

20. A stacker provided with an oscillatory tube, a drive-shaft having direct connection with the tube for oscillating the latter, and means for automatically reversing the movement of the tube.

21. A stacker provided with an oscillatory tube, a drive-shaft, a reversing mechanism mounted on the shaft and having direct communication with the tube, and a direct flexible connection between the shaft and the tube for oscillating the latter, said flexible connection in its operation being wound upon its said connecting members in opposite planes.

22. A stacker provided with an oscillatory tube, a drive-shaft, driving members mounted upon the shaft, means for clutching the driving members alternately to the shaft, and a single means connected with both driving members and to the tube for movement by the driving members to oscillate the tube.

23. A stacker provided with an oscillatory tube, a drive-shaft, winding-drums mounted loosely upon the shaft and having clutch members, a cable arranged with the tube and attached to the winding-drums to be wound thereon alternately, and a clutch-sleeve splined on the shaft and adapted to engage with the said clutch members of the drums interchangeably.

24. A stacker provided with an oscillatory tube having a drum, a drive-shaft having winding-drums mounted loosely thereon, a flexible connection wound upon the drum of the stacker-tube and attached at its ends to the winding-drums, and means for clutching the winding-drums alternately to the shaft.

25. A stacker provided with an oscillatory tube, a drive-shaft, a direct flexible connection between the shaft and tube, and means actuated by movement of the tube for reversing the direction of movement of the flexible connection.

26. A stacker provided with an oscillatory tube, a drive-shaft, a direct flexible connection between the shaft and the tube, and means for automatically reversing the direction of movement of the flexible connection for oscillating the tube.

27. A stacker provided with an oscillatory tube, a drive-shaft, winding-drums mounted loosely upon the shaft, a cable engaged with the stacker-tube and attached to the winding-drums, and means actuated by movement of the stacker-tube for clutching the winding-drums alternately to the shaft.

28. A stacker provided with an oscillatory tube, a revolving support for the tube, a drive-shaft carrying a reversing mechanism and driving members, said reversing mechanism having direct connection with the tube-support and actuated thereby, and a direct connection

between the said driving members and the tube for oscillating the latter.

29. A stacker provided with an oscillatory tube, a revolving support for the tube, said support having projections depending from its under surface, a drive-shaft carrying a reversing mechanism and driving members, said reversing mechanism having direct connection with the tube-support and actuated by the said projections, and a direct flexible connection between the driving members and the tube for oscillating the latter.

30. A stacker provided with an oscillatory tube, a drive-shaft carrying winding-drums loosely mounted thereon, and a sectional flexible connection between the winding-drums and the tube for oscillating the latter.

31. A stacker provided with an oscillatory tube, a driving mechanism consisting of a single shaft having driving members loosely mounted thereon, a two-part connection between the tube and the driving members for oscillating the tube, and means actuated by the movement of the stacker-tube for reversing the direction of movement thereof.

In testimony whereof we affix our signatures in presence of two witnesses.
